UNITED STATES PATENT OFFICE

170,546

SELF-ADJUSTING PERSONAL PROTECTIVE SHIELD

John L. Paul, Los Angeles, Calif., assignor to Lockheed Aircraft Corporation, Burbank, Calif.

Application February 9, 1953, Serial No. 23,491

Term of patent 14 years

(Cl. D3—26)

To all whom it may concern:

Be it known that I, John L. Paul, a citizen of the United States, residing at Los Angeles, in the State of California, have invented a new, original, and ornamental Design for a Self-Adjusting Personal Protective Shield, of which the following is a specification, reference being had to the accompanying drawings, forming a part hereof.

Figure 1 is a perspective view of a self-adjusting personal protective shield showing my new design;

The dotted indications of the tie strings shown in Fig. 1 are for illustrative purposes only.

I claim:

The ornamental design for a self-adjusting personal protective shield, as shown and described.

JOHN L. PAUL.
